United States Patent Office.

CHARLES B. MAEDEL AND JACOB WOLFF, OF CHICAGO, ILLINOIS.

Letters Patent No. 77,061, dated April 21, 1868.

IMPROVEMENT IN SKATE-FASTENING.

The Schedule referred to in these Letters Patent and making part of the same.

TO ALL WHOM IT MAY CONCERN:

Be it known that we, CHARLES B. MAEDEL and JACOB WOLFF, of Chicago, Cook county, Illinois, have invented certain new and useful Improvements in "Skate-Fastenings;" and do hereby declare that the following is a full, clear, and exact description thereof, reference being had to the accompanying drawings, and to the letters of reference marked thereon, making a part of this specification.

Figure 1 represents a side view of the hook as constructed.

Figure 2, a plan view of the same.

Figure 3, a view of the eyelet-screw; and

Figure 4, a side elevation of the skate with its fastening, and the foot of a person attached to the skate.

In the annexed drawings, A represents a metallic bar, which is L-shaped, and has an eyelet-hole at one end, and a shoulder formed (by slightly bending the bar) at the other. B represents an ordinary eyelet-screw, which is used for connecting the upper end of the bar A to the rear part of the heel of the boot or shoe of the skater. D represents the skate-wood, having the usual skate-iron C. E represents the heel-calk of the skate, and H the heel of the skater. The bar A is attached to the rear part of the skate, one prong of it being inserted between the wood and the skate-iron, with the heel-calk E passing up through its loop, as seen in fig. 4, and the other prong extending up the side of the heel H, so that when it is necessary to attach the skate, the eyelet-screw is inserted into the heel, as shown, the loop thereof being around the bar A, under its shoulder.

Thus it will be seen that the bar A is firmly attached to the skate, and the rear end of said skate may be easily and quickly secured to the skater. A strap, F, secures the toe of the foot in the usual manner.

This mode of fastening the skate is cheaper, substantial, and more quickly accomplished than others now known.

Having thus fully described our invention, what we claim as new, and desire to secure by Letters Patent, is—

The bar A, L-shaped, provided with a loop at one end, and having a shoulder at its other, when connected to the skate by the heel-calk E, and to the boot or shoe-heel by the eyelet-screw B, in the manner substantially as and for the purposes set forth.

CHARLES B. MAEDEL,
JACOB WOLFF.
